EVACUATOR

Robert T. McElvenny, 900 N. Michigan Blvd., Chicago, Ill.; Harold I. Snyder, 1458 5th St. NW, New Philadelphia, Ohio; and Gregory B. Sullivan, 2239 W. 119th St., Blue Island, Ill.; said Sullivan assignor of one-third to said McElvenny

Filed July 14, 1960, Ser. No. 42,889
14 Claims. (Cl. 128—278)

The invention relates to evacuators and more particularly to surgical evacuators for the removal of fluid from the human body and the like. The present invention has among its objects the production of an evacuator structure for use in the evacuation of fluids from the human body which is capable of handling 150 cc. or more fluid and which is capable of producing a negative pressure or suction equal to a column of water of 26 mm. or more in height, rendering the service extremely effective for the purposes intended.

Another object of the invention is the production of an evacuator structure which eliminates the need for electrical or mechanical pumps or the like, and which is very simple in construction and relatively inexpensive to manufacture, whereby the device may be packaged in sterile form with all necessary accessories such as tubing, needles, mounting elements and the like, whereby the item may be stocked and used as a one-time operation, and subsequently discarded.

A further object of the invention is the production of an evacuator having the above features which is relatively unbreakable, foolproof, and provided with all necessary means to permit its attachment to the body of the user, thereby eliminating any possibility of a failure of operation as a result of disengagement of the tube or the like which might otherwise result from movement of the patient or other reasons, and permitting it to be readily employed for use on ambulatory patients and the like.

Many other objects and advantages of the present invention will be obvious to those skilled in the art from the disclosure herein given.

In the drawings, wherein like reference characters indicate like or corresponding parts:

FIG. 1 is a front view of a portion of a human body illustrating the application of the present invention thereto in a radical breast dissection or breast removal;

FIG. 2 is a front view of a portion of a human leg illustrating the application of the present invention to an operation on a broken tibia;

FIG. 3 is a view similar to FIG. 2 following completion and suture of the wound illustrated in FIG. 2;

FIG. 4 is a plan view of the evacuator unit illustrated in FIG. 1;

FIG. 5 is a sectional view taken approximately on the line 5—5 of FIG. 4;

FIG. 6 is an enlarged sectional view, similar to FIG. 5, of a portion of the structure illustrated in FIG. 5, illustrating the evacuator unit in a collapsed or operative position;

FIG. 7 is an enlarged figure of a portion of the tubing employed, with portions thereof shown in cross section and illustrating the engagement therewith of the needle used in installing the tubing in a wound or the like; and

FIG. 8 is a plan view, with portions in sections, of a Y connector member by means of which two evacuating tubes may be connected to a single evacuator unit.

The present invention contemplates the use of a very simple container structure which readily adapts itself for manufacture out of plastic or other material and which is so designed that upon a partial collapsing, adapted to be readily performed manually, the container will tend to

2

resume its original shape, creating a negative pressure or partial vacuum therein, so that by the use of suitable tubing the container interior may be operatively connected with the interior of a wound or the like, operative to draw fluids from the latter into the container under the action of the reduced pressure therein. Suitable means may be readily provided, enabling reestablishment of the reduced pressure following depletion thereof as fluids are withdrawn from the wound into the container. The evacuator unit may be so designed that it may be strapped or otherwise applied to the body of the user to insure that it will be maintained at all times in operative position, and at the same time permitting the patient to be ambulatory.

Typical applications of the present invention in the surgical field, for example, and not by way of limitation, are:

(1) In large surgical fields developed in operations such as radical breast and neck dissections, abdominal, perineal and certain chest procedures.

(2) In evacuating hematoma in such operations as upon the hip, femur, tibia, forearm or hand.

(3) To evacuate joint fluid following knee joint operations and the like.

(4) Compound fractures.

(5) The treatment of large soft tissue abscesses and the like.

(6) In the treatment of chronic osteomyelitis, septic joints and the like.

(7) Other uses, as for example, the replacement of catheters now employed in many situations.

The use of drains in wounds is quite common, ordinary operative wounds normally being drained for a period of forty-eight hours after the operation. Extensive procedures or operations such as hip reconstructions and femoral shaft procedures yield three hundred to eight hundred cc. of blood and serum during the first forty hours. The next eight hours normally shows a diminishing return until near the end of the forty-eight hour period little if any material is recovered, following which the drains or tubes may be removed. The use of effective measures to withdraw such fluids results in a number of improved conditions. Swelling is kept at a minimum and suture tension is markedly decreased, with noticeably less post operative pain, and the wound edges are kept white, flat and quiescent.

The elimination of hematoma, swelling and tension also eliminates some encouraging factors for infection.

The tubing employed inside the body is constructed of plastic or other material which is non-reactive to the body constituents and is constructed with walls which are rigid as distinguished from collapsible, the tube being of a size to accommodate the fluids as they accumulate and, as hereinafter described in detail, we have found that a tubing which will fit a sixteen gauge needle, is very satisfactory for the purposes intended.

In use, a portion of the tubing, usually a free end thereof in the case of single tubes, may be suitably inserted in the wound as hereinafter described in detail, following which it is operatively connected to the evacuator container unit which is suitably manually actuated to create a negative pressure within the container whereby fluids will be drawn from the wound into the container. Straps or other suitable means may be provided to permit the securement of the evacuator container or unit to the body of the user or patient.

Referring to the drawings and more particularly to FIG. 1, the reference numeral 1 indicates generally an evacuator container or unit, the interior of which is adapted to be placed under a reduced or negative pressure compared with that of the exterior. In the illustration which shows the application of the invention to a breast operation, a

pair of tubes 2 are inserted in the wound and operatively connected to the container 1 by a connecting or lead-away tube 3 and manifold means formed as a Y-shaped connector member 4 operative to connect the tube 3 to the tubes 2, with the container unit 1 being mounted on the lower chest or stomach of the user by suitable means such as a plurality of straps 5, as hereinafter described in greater detail. It will be noted from a reference to FIG. 1 and as will be apparent from the description of FIGS. 2 and 3 hereinafter given, the tubes within the wound are not brought out through the incision, such as the incision 6 illustrated in FIG. 1, but rather a point spaced therefrom whereby the tube passes through healthy tissue and from which the tube, following completion of its intended use, may be readily withdrawn, leaving a small opening which will readily heal.

The Evacuator Unit

Referring to FIGS. 4 through 6, the embodiment of the invention illustrated employs an evacuator container or unit 1 which is constructed of relatively thin flexible or pliable plastic, or other suitable material, the unit 1 illustrated comprising a generally circular top wall 7, a generally similarly shaped bottom wall 8 and an annular shaped side wall 9. As illustrated in FIG. 6, the top and bottom walls 7 and 8 are secured to the adjacent edges of the side wall 9 by two seam lines 11 which may be formed as a suitable bond or weld resulting from the application of heat and pressure to the portions to be joined, the free edge portions 12 of the top and bottom members extending beyond the outer weld line, permitting it to fold inwardly as illustrated in FIG. 6.

Mounting flaps 13 may be integrally formed with the bottom wall 8, the flaps as illustrated in FIG. 6 preferably being provided with a reinforcing ring 14 of similar material and secured thereto by suitable means such as heat and pressure welding or the like, the flaps thus being provided with an opening 15 through which the mounting straps 5 may be passed.

Positioned within the container are a pair of oppositely disposed members 16 and 17 which, in the construction illustrated, may be identical in shape and size, the members illustrated being circular in shape and having a diameter substantially equal to the inner diameter of the top and bottom walls. The members 16 and 17 are made from relatively rigid material such as a suitable plastic or the like, and may be provided with a suitable means, as for example, a plurality of inturned oppositely disposed cylindrical bosses or shoulders 18, for maintaining respective compression springs 19 in operative position between the members 16 and 17, four such springs being employed with each member 16 and 17 having a like number of portions 18 formed therein.

The container may be provided with a suitable fluid outlet, illustrated as being formed by a tubular member 21, having an outwardly extending flange 22 thereon which is secured in fluid tight relation to the upper wall 7 by suitable means such as cementing, welding or the like. The outlet member illustrated is aligned with one of the spring aligning portions 18, top wall 7 being provided with an opening 23 therein to operatively connect the interior of the container, through the portion 18, with the interior of the outlet member 21, the latter being releaseably closed by a suitable stopper member 24 which may be provided with suitable means, such as a flat relatively thin strip 25, which may be manually grasped to facilitate the insertion or removal of the stopper 24 from the member 21.

The tube 3, forming the means by which fluid may enter the container 1, is suitably secured at its adjacent end to the container, as for example, by providing the tube with an outwardly extending flange 26 which may be suitably secured to the wall 7, the tube 3, in the construction illustrated, being aligned with one of the spring aligning portions 18 and operatively connecting with the interior of the container through an opening 27 formed in the top

wall 7 and the interior of the aligned portions 18. If desired, the strip 25 associated with the stopper 24 may be provided with an apertured free end 28 having a hole 29 therein, the strip 25 being of a length to permit the tube 3 to be inserted through the opening 29 so that the stopper 24 cannot be lost from the unit. Likewise, to insure a firm connection between the stopper and the inlet tube 21, the latter may be tapered or flared slightly and the stopper complementally formed as disclosed in FIG. 6.

As illustrated in FIG. 7, the tubing 2 which is adapted to be inserted into the wound is constructed from a suitable material which is inert to the body fluids and tissue, the tube being relatively flexible but having a wall thickness which will provide in effect a rigid tube wall which will adequately resist collapse under the operational conditions involved. We have found that a tube having an internal diameter of approximately one-sixteenth of an inch is adequate for most applications of the invention, the tube having an external diameter of approximately one-eighth of an inch. As illustrated in FIG. 2, the free end 2a of the tube may be provided with a plurality of apertures 31, the length of the apertured portions varying as to the particular application in which it is to be employed, with an initial length of eight inches, which if desired may be shortened by cutting off the tube, being sufficient for most applications. In the embodiment shown in FIG. 7, the tube is provided with apertures 31 having a diameter of approximately forty-thousandths of an inch and axially spaced substantially one-quarter of an inch, the apertures being diametrically positioned on opposite sides of the tubing and conveniently formed by punching or other suitable operation. Thus, perforations 31 may be readily produced by punching with a member having a diameter of approximately fifty-six thousandths of an inch and following the punching operation the material at the perforations will flow slightly to reduce the diameter of the perforations to approximately forty-thousandths of an inch.

The tubing thus far is of a size which may be readily affixed to a needle, indicated generally by the numeral 32, of a size substantially equal to that of a 16-gauge needle, which is provided with a suitable point 33 at one end and a mounting stem 34 at the opposite end, having external threads 35 thereon. The stem 34 is connected to the needle body by a neck portion 36 of reduced diameter, whereby the stem may be screwed into the adjacent end 2b of the tubing 2 and affixed thereto by the threads 35, the end of the tube extending into the neck portion 36, as illustrated in FIG. 7, whereby the end of the tube will not interfere or engage the flesh as the needle and tube are drawn therethrough.

Operation of the Device

In use, as illustrated in FIG. 2, prior to suturing of the wound W one or more tubes are placed with their perforated ends in the wound, the perforations preferably being positioned at the points where evacuation is desired, the opposite end 2b of the tube being brought through sound tissue as illustrated at 37 and 38, such insertion being accomplished by insertion of the needle 33 and connecting tubing 2 from within the wound outwardly through the healthy tissue. Following the placing of the tube or tubes in the manner illustrated, the wound is closed by suturing in the usual manner. The tube may then be cut adjacent the connection thereof with the needle 33 to sever the latter and provide a clean tube end which may be inserted either into the lead away tube 3, operative to connect the tube 2 with the evacuator unit 1, or if two tubes are employed as illustrated in FIGS. 1 or 2, the corresponding ends of the tubes, may be operatively connected to the lead away tube 3 by a suitable manifold means formed as Y-shaped connector 4 which may be constructed of plastic or other suitable material, the connecting leg 39 thereof having an internal diameter capable of receiving the adjacent end of the lead away tube 3 in a tight fit by means of which the connector 4 will be firmly at-

tached to the tubing 3. The opposite legs 40 are provided with end portions of a size to accommodate the smaller tubing 2, adapted to engage the latter in a firm friction grip which will retain the tubing operatively connected under all normal conditions.

If desired, instead of using a pair of tubes as illustrated in FIGS. 1 and 2, in some conditions a single tube may be satisfactory, such construction being illustrated in FIG. 3 wherein the single tube 2' is provided with a perforated intermediate portion 41 which is adapted to be inserted into the wound, both ends of the tube being brought out of the exterior and operatively connected by suitable means such as a connector 4 to the lead away tubing 3.

Following the operative connection of the tubing 2 and 3, the stopper 24 may be temporarily removed from the outlet 21 and pressure applied to the top and bottom walls 7 and 8, as for example, by manually squeezing the container, to collapse the intermediate wall 9 and move the top and bottom walls toward one another to a position similar to that illustrated in FIG. 6. While the walls 7 and 8 are so positioned, the stopper 24 is reinserted into the outlet 21 and pressure on the container released, whereby the compression springs 19 will urge the members 16 and 17 in opposite directions, thus tending to expand the container to its original shape and size and thereby create a negative pressure or vacuum in the container unit 1, which through the tubing 3 and tube or tubes 2, will tend to draw any accumulated fluids within the wound into the container 1, such action continuing until the container has been filled to a point where the action of the springs 19 is exhausted. At such time the stopper 24 may be removed and any fluids drained from the container, following which the latter may be collapsed as previously described and the stopper reinserted to restore the original conditions.

To facilitate the desired operations, and permit persons, otherwise able, to be ambulatory, straps 5 or other suitable means may be employed to mount the container unit 1 on the body of the user. Thus in the example illustrated in FIG. 1, the unit 1 may be mounted on the lower chest or abdomen of the user by means of the straps 5 which may be passed through the openings 15 in the straps 13 to position the strap beneath the bottom wall 8, following which the strap may be passed around the body of the user and the free end secured by suitable buckles 42 or the like. In cases such as illustrated in FIGS. 2 and 3, the container may be strapped about the thigh of the user or otherwise attached, at a suitable location, to the user's body.

After the unit has served its purpose, the tubing 2 may be suitably removed from the body of the user, such tubing being withdrawn from the wound in those cases where the free end of the tubing is positioned in the wound, and in those cases such as illustrated in FIG. 3 the tubing is sterilized and cut adjacent one end of its exit from the body, following which the other end is tensioned to withdraw the tubing.

It will be noted from the above that we have provided an evacuator structure which is very efficient in use, yet sufficiently simple in construction and inexpensive to manufacture to permit its use as a one time operation, whereby each case would employ a new unit, thereby eliminating cleaning problems, etc. Preferably the device would be packed as a complete kit in a suitable sterile wrapping or envelope, each kit containing an adequate supply of tubes and needles, together with the container unit, connectors, mounting straps, etc., whereby each package is self-contained with all items necessary for the application which is to be made thereof.

Having thus described our invention, it will be obvious to those skilled in the art from the disclosure herein given that various modifications may be made in the same without departing from the spirit of our invention; hence we do not wish to be understood as limiting ourselves to the

exact form, construction, arrangement and combination of parts herein shown and described, or uses mentioned.

What we claim as new and desire to secure by Letters Patent is:

- 5 1. A self-contained, independently operable evacuator structure for the extraction of body fluids, for ambulatory human use, said evacuator structure comprising a fluid tight container formed from flexible material, said container having circular top and bottom walls connected at their peripheral edges by an annular shaped wall, a pair of circular members of approximately the same size as the interior portions of said top and bottom walls and disposed within said container adjacent such walls, a plurality of springs disposed between said members with the opposite ends of each spring engaging the respective members to exert a separating force thereon, oppositely disposed inwardly extending means on said members engageable with said springs to retain the latter in operative position, one of said circular container walls including an inlet tube connected thereto in fluid tight relation, an outlet also provided in the aforesaid container wall, means releasably sealing said outlet, the opposite wall being provided with a plurality of outwardly extending flaps constructed to operatively receive means for maintaining the container on a body, a fluid receiving tube operatively connected in fluid tight relation to said inlet tube, said fluid receiving tube being flexible and having relatively non-collapsible side walls, a portion which is provided with a plurality of generally radially extending openings therein operatively communicating with the tube exterior, said last mentioned portion being adapted to be inserted into a wound with said openings forming fluid inlets, said circular members being operative when moved by collapsing of said container to compress said springs, to create a negative pressure in said container to draw fluid through said tube into the container.

- 20 2. An evacuator structure as defined in claim 1, wherein said fluid receiving tube is constructed for manual connection with said inlet tube, and a needle is provided with a point at one end and means at the other end engaging and securing the end of said fluid receiving tube engageable with said inlet tube for drawing the adjacent end portion of the fluid receiving tube through flesh, outwardly from a wound to be evacuated.

- 25 3. A self-contained, independently operable evacuator structure for the extraction of body fluids, for ambulatory human use, said evacuator structure comprising a fluid tight container formed from flexible material, said container having top and bottom, and side walls, a pair of members of approximately the same size as the interior portions of said top and bottom walls and disposed within said container adjacent such walls, a plurality of springs disposed between said members with the opposite end of each spring engaging the respective members to exert a separating force thereon, one of said container walls including an inlet tube connected thereto in fluid tight relation, an outlet also provided in the aforesaid container wall, removable means releasably sealing said outlet, a fluid receiving tube operatively connected in fluid tight relation to said inlet tube, said fluid receiving tube being flexible and having relatively non-collapsible side walls, a portion which is provided with an opening therein operatively communicating with the tube exterior, said last mentioned portion being adapted to be inserted into a wound with said opening forming a fluid inlet, said members being operative when moved by collapsing of said container to compress said springs, to create a negative pressure in said container to draw fluid through said tube into the container, and an outwardly extending flap provided on one of said walls constructed to operatively receive means for maintaining the container on a body.
- 40 4. A self-contained, independently operable, evacuator for the extraction of body fluids, for ambulatory human use, said evacuator comprising in combination, a container formed of flexible material, said container having a pair

of oppositely facing end walls and a connecting side wall arranged for movement of the end walls relatively toward each other to reduce the volume of the container, said container being resiliently compressible when subjected to manual pressure and upon release of said manual pressure being resiliently expandable to a normal expanded position, said container having an opening in one wall thereof, a conduit of flexible tubing connected at one end to said container opening, the other end of said tubing being of a material compatible with human tissue and being arranged for insertion into a body wound, means forming a part of the evacuator and forming an exhaust opening in communication with said container, and closure means for said exhaust opening, whereby upon compression and release of said container with the tubing end inserted into a body wound, and upon closure of said exhaust opening, body fluids will be extracted from the wound by continuous suction upon expansion of the container and expressed into the container for storage therein.

5. An evacuator as defined in claim 4 wherein said other end of said flexible tubing is provided with a multiplicity of juxtaposed openings for insertion into said body wound.

6. An evacuator as defined in claim 4 wherein a plurality of springs is provided within the container for effecting the resilient expansion thereof upon release of said manual pressure.

7. An evacuator as defined in claim 4 wherein said container is provided with strap fastening means, and wherein said evacuator further includes a strap member arranged to be secured to said fastening means and to the body of a human for supporting the container therefrom, whereby to facilitate the ambulatory human use of said evacuator.

8. An evacuator as defined in claim 4 wherein said closure means for said exhaust opening comprises a selectively operable manual valve.

9. An evacuator as defined in claim 8 wherein said valve comprises a valve plug insertable into the exhaust opening in the container, and a strap anchored to the containing carrying said plug.

10. A self-contained, independently operable, evacuator for the extraction of body fluids, for ambulatory human use, said evacuator comprising in combination, a container formed of flexible material, said container having a pair of oppositely facing end walls and a connecting side wall arranged for movement of the end walls relatively toward each other to reduce the volume of the container, said container being resiliently compressible when subjected to manual pressure and upon release of said manual pressure being resiliently expandable to a normal expanded position, said container having an opening in one wall thereof, a conduit of flexible tubing connected at one end to said container opening, the other end of said tubing being of a material compatible with human tissue and being arranged for insertion into a body wound, a needle removably connectable to said tubing for drawing said other tubing end into said body wound, means forming a part of the evacuator and forming an exhaust opening in communication with said container, and closure means for said exhaust opening,

whereby upon compression and release of said container with the tubing end inserted into a body wound, and upon closure of said exhaust opening, body fluids will be extracted from the wound by continuous suction upon expansion of the container and expressed into the container for storage therein.

11. An evacuator as defined in claim 10 wherein said needle is sharpened at one end, and is provided at its other end with threads for removable connection to said tubing.

12. A self-contained, independently operable, evacuator for the extraction of body fluids, for ambulatory human use, said evacuator comprising in combination, a container formed of flexible material, said container having a pair of oppositely facing end walls and a connecting side wall arranged for movement of the end walls relatively toward each other to reduce the volume of the container, said container being resiliently compressible when subjected to manual pressure and upon release of said manual pressure being resiliently expandable to a normal expanded position, said container having an opening in one wall thereof, a conduit of flexible tubing comprising a first tubing portion connected at one end to said container opening, a second tubing portion of a material compatible with human tissue arranged for insertion into a body wound, and a connector removably interconnecting said tubing portions, means forming a part of the evacuator and forming an exhaust opening in communication with said container, and closure means for said exhaust opening, whereby upon compression and release of said container with the tubing end inserted into a body wound, and upon closure of said exhaust opening, body fluids will be extracted from the wound by continuous suction upon expansion of the container and expressed into the container for storage therein.

13. An evacuator as defined in claim 12 wherein said first tubing portion is of larger size, and said second tubing portion is of smaller size, and said connector comprises adaptor means for accommodating and interfiting said tubing portions of different size.

14. An evacuator as defined in claim 12 wherein said first tubing portion comprises a single reach and said second tubing portion comprises a plurality of reaches in parallel, and said connector comprises adaptor means for accommodating and interfiting said single and multiple tubing reaches.
